DESIGN FOR A WOMAN'S OVERALL ENSEMBLE

Clarice L. Scott, Silver Spring, Md., Helen Shelby,
Washington, D. C., Mildred Carney, Ithaca, N. Y., and Gladys Meloche, Madison, Wis., as signors to the United States of America as represented by Chester C. Davis, Administrator of the War Food Administration, and his successors in office

Application October 16, 1943, Serial No. 111,408

Term of patent 3½ years

To all whom it may concern:

Be it known that we, Clarice L. Scott, of Silver Spring, Maryland, Helen Shelby, of Washington, D. C., Mildred Carney, of Ithaca, New York, and Gladys Meloche, of Madison, Wisconsin, citizens of the United States of America, have invented a new, original, and ornamental Design for Woman's Overall Ensemble, of which the following is a specification, reference being had to the accompanying drawing forming part thereof.

Fig. 1 is a front view of a woman's overall ensemble, in partially open position, showing our design; and

Fig. 2 is a rear view of the woman's overall ensemble shown in Fig. 1, in a closed position.

We claim:

The ornamental design for a woman's overall ensemble, as shown.
